United States Patent Office

Des. 178,725
Patented Sept. 11, 1956

178,725

BELT

Marian M. Flynn, Chicago, Ill.

Application August 17, 1954, Serial No. 31,897

Term of patent 3½ years

(Cl. D3—10)

FIG. 1.

FIG. 2.

FIG. 3.

Fig. 1 is a front perspective view of a belt showing my new design;

Fig. 2 is a top plan view of the belt as it appears in unfastened position; and

Fig. 3 is a bottom plan view thereof.

I claim:

The ornamental design for a belt, substantially as shown.
